UNITED STATES PATENT OFFICE.

JASPER S. COXEY, OF SPOKANE, WASHINGTON.

MECHANICAL TOY.

1,387,923.

Specification of Letters Patent. Patented Aug. 16, 1921.

Application filed January 19, 1920. Serial No. 352,270.

To all whom it may concern:

Be it known that I, JASPER S. COXEY, a citizen of the United States, residing at Spokane, in the county of Spokane and State of Washington, have invented certain new and useful Improvements in Mechanical Toys, of which the following is a specification.

This invention relates to a mechanical toy 10 operating to simulate a horse race and dancing figures.

In the construction of mechanical toys designed to depict a realistic race it is difficult to impart to the moving figures that element of chance which is present in an actual race and therefore renders the event so interesting in that there is no predetermined outcome. In this invention there is present a mechanical construction such that a number 20 of figures moving to simulate a race are so driven that it is impossible to determine, in advance, the outcome of the race.

There is another feature of the invention, as regards the drive of the figures, which is 25 a departure from the usual construction in that there is provided a mechanism for moving several figures simultaneously in the same direction, each figure moving independently of the others and at speeds irregularly varying through a considerable range so that the figures of the device pass and repass each other without any particular order or control on the part of the manipulator of the toy.

30 A chance mechanism for stopping the figures at the end of the race is still another feature of the invention.

Another feature is the provision of dancing figures operated by the same mechanism 40 that drives the racing figures and so arranged that one or more pairs of figures dance intermittently during a race.

In the drawings—

45 Fig. 1 is a perspective view of the toy.
Fig. 2 is a perspective view of the toy mechanism.

Fig. 3 is a top plan view of the dancing figure mechanism.

50 Fig. 4 is a front elevation of the dancing figure mechanism.

Fig. 5 is a vertical section through the driven pulleys carrying the racing figures, and

Fig. 6 is a side elevation of a stop star. In detail, a base 1 carries a block 2 mounted at the center thereof and which supports a bracket 3 in which a plurality of pulleys 4, 5, 6 and 7 are mounted, the uppermost pulley 4 being provided with an annulus 8 on its upper face riding in a corresponding groove in the plate 9 carried on the upper part of the bracket 3. The pulleys 5 and 6 each carries a similar annulus entering a corresponding groove in the superposed pulley, the pulley 6 also having an annulus 10 on its bottom face and pulley 7 being provided with a groove to receive the said lower annulus. The pulley 7 has a raceway in its lower face accommodating balls 11 running on a plate 12, similar ball bearings 13 being provided between the opposed faces of all the pulleys. The peripheries of the pulleys 4, 5, 6 and 7 are grooved as shown to receive belts 14, 15, 16, 17 and 18 for purposes to be hereinafter set forth.

75 The pulleys 4, 5, 6 and 7 are provided with axially aligned central holes, the holes being graduated in size toward the bottom pulley which has the smallest hole and standards 19, 20, 21 and 22 rise from the respective 80 pulleys through the holes in the superposed pulleys, as shown in Fig. 5, so that as the pulleys are revolved their respective standards 19, 20, 21 and 22 revolve one within the other. These standards are extended 85 laterally at their upper ends as shown in Fig. 1 and are then bent downwardly and attached to figures simulating race horses with jockeys, as indicated at 23, 24, 25 and 26 respectively, which move adjacent the top 90 cover 27 of a box 28 to be later described.

At one corner of the base 1 is a spring motor 29 having a winding spindle 30, a governor 31, a control lever 32 and a governor stop element 33 all of which may be of 95 any standard construction similar to that used in a disk phonograph. The driving shaft 34 of said spring motor 29 is extended and carries a beveled pinion 35, said shaft being supported adjacent the pinion 35 by 100 an upright 36. At right angles to the motor shaft 34 and mounted in supports 37 and 38 is a driven shaft 39 having a beveled pinion 40 meshing with the pinion 35 and having end portions journaled in said standards 105 37 and 38, an intermediate portion 41 of

said shaft being angular in cross section to receive a pulley 42 having a very irregular face, that is to say, the said pulley 42 is provided with undulations on its surface, which 5 undulations run circumferentially of the pulley. The pulley 42 is mounted on the angular portion 41 of said shaft, as stated, and may reciprocate thereon. To accomplish this movement the said pulley 42 carries a 10 finger 43 having a dog 44 running in the threads of a reversible screw or two-way helices 45 which is fixed by means of a screw 46 to the support 38 and thus as the shaft 39 is driven the pulley 42 will be reciprocated back and forth thereon. The belts 15 14, 15, 16 and 17 previously mentioned as running on the pulleys 4, 5, 6 and 7 are trained over the pulley 42 and guided by vertical fingers 47 carried on a support 48 20 and by horizontally extending fingers 49 carried on a support 50. These belts are more or less elastic and therefore as the motor shaft 34 drives the pulley 42 and the said pulley 42 reciprocates the irregular surface 25 thereof will drive the pulleys 4, 5, 6 and 7 at irregularly varying speeds and thus the figures 23, 24, 25 and 26 will be moved in the same direction at irregularly varying speeds and thereby caused to pass 30 and repass each other without any particular order making it impossible to determine the position which will be maintained by any particular figure with respect to the other figures during movement. The figures 23, 35 24, 25 and 26 each carry a dog 51. Adjacent the top 27 of the box 28 and carried on brackets 52 is a shaft 53 carrying stars 54, 55, 56 and 57 one of which is typically illustrated in Fig. 6 and, as will be observed, has 40 a series of equal points 58 and one long point 59. Adjacent these stars is mounted a cross bar 60 carried on supports 61 and connecting with the governor stop lever 33 of the spring motor so that as said member 60 45 is depressed the motor will be stopped until again set for operation by the stopping and starting lever 32 which projects through the side of the box 28. The racing figures moving around an arena or race course 62 laid 50 off by posts 63 on a base plate 64 on the top of the box 28 will, by reason of the dogs 51 engage the respective star wheels located in their paths and projecting through corresponding slots in the top 27 of the box 28 55 and will revolve said stars so that eventually some one figure, after having engaged all the points of the star, will cause its long point 59 to engage the member 60 and stop the motor thereby indicating a finish of the race. As will be seen from the construction 60 described these stars are loosely mounted and are revolute by the figures which move at irregularly varying speeds with respect to each other and thus there is a two-fold 65 element of chance involved in the operation

of the figures, namely the speed at which they move with respect to each other and the means by which they are stopped to indicate a finish of the race. In this way a very realistic race is staged by the operation of 70 the figures. The spring motor 29 may be wound by means of the winding key 65 working through an escutcheon 66 on the side of the box 28. The box 28 is suitably bound at the corners by corner pieces 67 to 75 prevent damage to the corners and adjacent one corner cut-outs 68 and 69 are provided.

Diagonally across the corner at which the cut-outs 68 and 69 occur and supported in uprights 70 is a shaft 71 which carries a 80 revolute element 72 having peripheral lugs 73 and 74, the shaft 71 carrying fingers 75 and 76. The sides of the member 72 are provided with radial corrugations or teeth 77. Vertical spindles 78 and 79 are mounted adjacent the shaft 71 and carry yokes 80 and 81 respectively which are provided with fingers 82 and 83 carrying figures simulating ballet dancers or the like. The yokes 80 and 81 carry, respectively, lugs 84 and 85 which 85 as said yokes are swung are caused to engage or be disengaged from the respective toothed surfaces of the member 72, said yokes being swung by the peripheral lugs 73 and 74 and the fingers 75 and 76. When either of the 90 lugs 84 or 85 engages the corrugations of the member 72 it is caused to chatter the yoke 80 or 81 and thereby vibrate its respective finger 82 or 83, causing the figures carried thereby to simulate dancing movement. As 95 will be seen from an examination of Fig. 2 of the drawings, the shaft 71 carries a pulley 86 which is driven from the pulley 7 by means of the belt 18. As the said shaft 71 revolves, carrying with it the member 72, 100 the lugs carried by the latter and the fingers carried by the former serve to intermittently swing the yokes 80 and 81 so that the figures carried thereby will dance, then remain inoperative in a retracted position within their 105 respective opening for a short time and then dance again. The motion of the dancing figures, like the motion of the racing figures is also controlled by the irregular surface pulley 42 and hence the said figures will 110 dance first fast, then slow, dependent on the particular surface of the pulley 42 with which the belt on the standard 7 is at that time in contact.

Having thus described the invention, what 115 is claimed as new is:

1. A toy comprising a plurality of superposed pulleys, each having a central opening, means for rotating said pulleys simultaneously at relatively varying speeds, standards 125 rising from the several pulleys through the openings in the superposed pulleys, figures carried by said standards, a brake device arranged below the paths of the several figures, star wheels in the respective paths of the sev- 130

eral figures and provided each with an elongated tooth to actuate said brake device, and means on the several figures to actuate the respective star wheels.

- 5 2. A toy comprising a rotatable shaft, means for rotating said shaft at an irregular speed, a yoke disposed adjacent said shaft, a

figure carried by said yoke, means on the shaft for swinging the yoke to advance or retract the figure, and means driven by said shaft to vibrate the yoke and the figure.

In testimony whereof I affix my signature.

JASPER S. COXEY. [L.S.]
